(57) **CLAIM**

The ornamental design for a vehicle food tray, as shown and described.

DESCRIPTION

FIG. 1 is a front-top-left perspective view of a vehicle food tray showing our new design;

FIG. 2 is a rear-bottom-right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof;

FIG. 8 is a left elevational view thereof;

FIG. 9 is a front-top-left perspective view of the vehicle food tray in a folded **20** configuration; and,

FIG. 10 is a rear-bottom-right perspective view thereof. The broken lines in FIG. 1 through FIG. 10 illustrate portions of the vehicle food tray which form no part of the claimed design.
